COLLECTOR SYSTEM FOR PIRNS

Karl Forkel, Beuel, Germany, assignor to Schweiter Ltd.,
Horgen, Switzerland, a corporation of Switzerland

Application January 29, 1952, Serial No. 268,872

Claims priority, application Germany February 6, 1951

8 Claims. (Cl. 53—236)

This invention relates to a collector system for elongated articles as used, for example, in weft winding machines having a conveyor arrangement to remove the wound pirns.

It is one of the primary objects of the invention to provide means affording the transfer of pirns in substantially parallel and aligned positions with respect to each other to a collector receptacle, whereby such collector system may be either built onto existing weft winding machines or may be readily incorporated in new winding machines so that the removal of the weft pirns is automatically achieved and the receptacle is charged with said pirns while the same remain in aligned and parallel positions with respect to each other.

It is another object of the present invention to provide means facilitating the supply of pirns and like elongated articles from conveyor means to collector means in a substantially orderly and predetermined fashion, whereby said pirns are supplied to or discharged into a collector receptacle gradually while their aligned positions are substantially maintained.

It has hitherto been usual to charge the elongated articles or weft pirns into a container by hand, or to allow them to fall down an inclined chute or a distributing hopper into a box. Falling freely, the pirns do not always align themselves parallel to one another, with the result that they have to be repositioned, or aligned, by hand. A particularly serious disadvantage, however, resides in the fact that owing to the impact of the pirns on falling the strength and the arrangement of the layers of yarn, especially in yarns of fine count, are adversely affected.

The drawbacks just referred to are eliminated by the present invention which renders the possibility of transferring a supply of pirns in parallel relation to each other along a conveyor arrangement from which said pirns are further moved onto a collector band reaching into a collector receptacle, whose top end is substantially level with said conveyor arrangement, said collector band under the influence and weight of said weft pirns receding into said receptacle without substantially disturbing the parallel and aligned relationship between the pirns thus discharged into the receptacle.

The collector band is preferably operatively connected to a brake roller for releasing said collector band step by step into said receptacle, whereby the collector band is partly wound around said roller and the braking or drag power of the latter is so calculated that the retraction of the band into the container under the weight of the weft pirns takes place gradually, so that the pirns, unable to fall indiscriminately, retain their parallel alignment.

The drawing shows diagrammatically a typical embodiment of the invention, in which drawing:

Fig. 1 is a lateral elevation of the invention showing only the essential parts;

Fig. 2 is an end elevation of the receptacle or container taking the form of a packing bag in its suspension device. A conveyor band 1, which expeditiously extends through

2

out the length of the weft winding machine (not shown), is driven in the direction of the arrows by a drive motor or by the main drive shaft of the machine through the intermediary of a wormwheel transmission gear (not shown), and conveys the elongated articles or pirns 2, as they arrive, in the leftward direction to the packing arrangement (Fig. 1). The paralleling device consists of a press-plate 4, adjustable for height and spring-mounted, is disposed in the path of the pirns, the reception end of which press-plate is slightly upturned and which press-plate encompasses the exact aligning of the weft pirns transversely to the lengthwise axis of the conveyor arrangement. Adjustment of the height of the press-plate 4 is effected by means of screws 3.

The weft pirns are then impelled into a flat channel consisting of an intermediate plate 5 and an upper member 5a. The thrust of the further weft pirns as they arrive impels forward those lying in front of them, which therefore pass on to a collector band 7 which is of a width approximately equal to the length of the weft pirns and, under the weight of the pirns, slowly recedes into the packing bag 12. The band is provided with eyelets which are slipped on to holding pegs 9 and 9a, and runs over a guide roller 6 on to a braked roller 8 on to which it is preferably partly wound.

The band or collector element 7 is provided with three portions, of which one portion extends into the path of the aligning or paralleling means 3—5, a second portion reaches into the receptacle or bag 12 and a third portion is engaged by releasing means 10, which includes a brake roller 8.

The braking and release arrangement, which forms operable means and may consist of a friction brake 10 and a loading weight 11, is so balanced that the subsidence of the band takes place gradually.

Designated by the numeral 13 is a flap which is kept open until the container is full. In order to avoid interruption of the operation of the weft winding machine from the moment of removal of the receptacle until the fitting of a new, empty receptacle, the flap 13 can be swung downwards into the position shown by the broken line, with the result that the weft pirns, as they arrive, will accumulate until the flap 13 is opened again.

When the bag 12 is full, the collecting band 7 is detached from the pegs 9 and 9a, and the bag itself, which is suspended by lateral flaps from the pegs 16 of the packing device, is detached and wheeled out of the packing device by means of a trolley plate 15 travelling on rails 14.

The trolley arrangement 14, 15 is important because it enables the personnel tending the weft winding machine, which personnel generally consists of one woman, to remove the packing bag, which may weigh anything up to about 155 lbs., unaided, and to suspend a new packing bag in its place, without interrupting the running of the machine. The packed bags can then be sewn up or made ready for transport in some other way.

Although in the embodiment illustrated the receptacle is shown as a packing bag, it is obvious that the inventive device can, without modification, be used in conjunction with other receptacles or containers, such as wooden cases, sheet metal bins, or the like.

In general it will be understood that my invention is not limited to the details of construction and operation described above and shown in the drawings except as appears hereafter in the claims, and that these claims are intended to include equivalents of the elements mentioned in them specifically as well as those elements themselves.

What I claim is:

1. In a collector system for pirns and like elongated articles; the combination of a receptacle having a top end, into which said pirns are to be discharged, a supporting frame, means for removably supporting said receptacle

3

on said frame when the former has been filled with pirs, means aligning said pirs in parallel relation next to each other and arranged substantially level with said top end of said receptacle, movably disposed collector band means arranged with one portion extending into the path of said aligning means and with another portion extending into said receptacle for maintaining said pirs transversely to the longitudinal axis of said collector band means, and means positioned adjacent said aligning means and operatively connected to said one portion of said collector band means and guiding the latter past said aligning means and for releasing said collector band means over the top end of said receptacle gradually toward the interior of the same in such manner, so that said pirs when coming from said aligning means are moved into said receptacle substantially undisturbed with respect to their aligned relation to each other.

2. In a collector system for pirs and like elongated articles; the combination of a receptacle having a top end, into which said pirs are to be discharged, a supporting frame, means for removably supporting said receptacle on said frame when the former has been filled with pirs, means aligning said pirs in parallel relation next to each other and arranged substantially level with the top end of said receptacle, movably disposed collector means having three portions, one portion extending into the path of said aligning means, the second portion extending into said receptacle for maintaining said pirs transversely to the longitudinal axis of said collector means, and operable means positioned adjacent said aligning means and operatively connected to the third portion of said collector means and guiding the latter past said aligning means and releasing said second portion of said collector means gradually toward the interior of said receptacle, so that said pirs when coming from said aligning means are moved into said receptacle substantially undisturbed with respect to their aligned relation to each other.

3. In a collector system according to claim 2, said aligning means including a spring-supported press plate, and conveyor means arranged opposite said press plate there-

below, whereby said pirs will be displaced by said conveyor means and are aligned between it and said press plate.

4. In a collector system according to claim 3, said aligning means further including substantially horizontal channel means through which said pirs are guided for engagement with said one portion of said collector means.

5. In a collector system according to claim 2, said operable means including a balanced roller with counter-weight, and interengageable means, respectively, on said roller and on said collector means for controlling gradual release of said second portion of said collector means into said receptacle.

6. In a collector system according to claim 2, said aligning means including conveyor means, plate means overlying a part of said conveyor means, whereby pirs freely transported by said conveyor means are brought into aligned position by said plate means, and channel means through which said pirs are guided in side-by-side relation and substantially parallel to each other, said channel means extending from said conveyor means to said other portion of said collector means for direct discharge of said pirs thereon.

7. In a collector system according to claim 6, said plate means being spaced from said conveyor means, the entrance to the space between said plate means and part of said conveyor means being greater in width than the diameter of a pirn.

8. In a system according to claim 7, including a flap pivotally supported by said plate means adjacent said entrance, whereby said entrance for said pirs to said space between said plate means and said conveyor means may be opened and closed.
